UNITED STATES PATENT OFFICE.

NICHOLAS CAMELO, OF LOS ANGELES, AND THOMAS DOMBROWSKI, OF SAN PEDRO, CALIFORNIA, ASSIGNORS TO ONEIDA SANI-SEAT COMPANY, INC., OF ROME, NEW YORK, A CORPORATION OF NEW YORK.

COIN-CONTROL APPARATUS.

Original application filed September 6, 1921, Serial No. 498,641. Divided and this application filed January 11, 1923. Serial No. 612,099.

To all whom it may concern:

Be it known that we, NICHOLAS CAMELO and THOMAS DOMBROWSKI, citizens of the United States, and residents, respectively, of Los Angeles, in the county of Los Angeles, State of California, and San Pedro, in the county of Los Angeles and State of California, have invented certain new and useful Improvements in Coin-Control Apparatus, of which the following is a specification.

Our present invention relates to coin controlled devices of the type illustrated and described, but not claimed, in our companion application Ser. No. 498,641, filed September 6, 1921, for vending machines, of which this application is a division, and our improvements consist in the novel features of construction, combination and arrangement 20 of parts to be set forth in detail hereinafter and particularly defined in the claim hereunto appended.

In the accompanying drawings which are illustrative of our improvements and wherein like characters of reference denote corresponding parts in the different views.

Figure 1 is a vertical section of a vending machine showing our improved coin control mechanism associated therewith, and 30 with the parts thereof in normal position;

Figure 2, a horizontal section showing in top plan the mechanism illustrated in Figure 1;

Figure 3, a view similar to Figure 1 showing the operation of the parts of the mechanism after a coin has been deposited in the device; and

Figure 4, a front elevation of the machine illustrated in previous figures.

In order that our improvements and their mode of operation may be more clearly understood, we will describe them as associated with a vending machine mechanism of the type disclosed in our companion application previously referred to. It will be understood, however, that our improvements are capable of association and use with vending machine mechanisms of other types and therefore, the present description in so far as it relates to the vending machine mechanism of our companion application should be construed broadly and not in any way as

limiting the range of beneficial utility to our invention.

Now by reference to the drawings it will be observed that in accordance with the foregoing we have illustrated our improved coin control device as associated with a vending machine mechanism including essentially a receptacle 10 adapted to receive articles A to be dispensed, said articles in the present instance being in form of folded sheets. The size, shape and material of the receptacle is relatively unimportant, but is shown as being formed of substantial sheet metal into rectangular shape with its lower portion reinforced by interiorly arranged front, rear and side upright pieces 11, while the bottom thereof is permanently closed by a base board 12. Slidably mounted in any suitable manner within this receptacle for projectile and retractile movement with respect to the front thereof is a plate 14 that is maintained normally retracted by one or more coil springs 15 connecting it with the rear upright piece 11. One or more rack bars 16 are secured to the under face of said plate for co-operation with a segment or segments 17 carried by a shaft 18 extending transversely of the receptacle and equipped with a handle 19 whereby the plate may be projected to eject the articles A through an elongated slot 20 in the front of the receptacle, ejection being effected by a forwardly extending lip 21 on the plate that is adapted to engage between the folds of the sheets in the manner indicated in Figure 3, and particularly described in our said companion application.

Fixed to and projecting inwardly from the front upright piece 11 is a pair of brackets 23 that support at their inner ends a relatively short transverse shaft 24 upon which a combined coin chute and detent is mounted for rotative movement. The detent 25 consists of an arm extending rearwardly from the shaft 24 and having its end notched or otherwise suitably shaped for engagement with the forward edge of the plate 14 whereby the latter is locked against forward or projectile movement when it is retracted. The chute 26 is formed either as an integral part of the detent 25 or as a separate element rigidly fixed thereto,

whereby both are movable in unison, and preferably the material constituting the detent and chute is so disposed with respect to the shaft 24 as to be balanced and to assume normally a position with the detent arm raised and its notched end in abutting locking contact with the forward end of the plate 14.

A coin slot 27 is formed in the front of the receptacle below the ejection slot 20 and the forward end of the chute 26 is disposed adjacent to said coin slot, so that a coin inserted in the latter will be received by said chute. The chute is normally disposed at a downward incline from its forward end and therefore a coin deposited in the coin slot immediately will roll to the rear thereof and through its weight act to slightly rotate the same and thereby disengage the detent from the plate 14, whereupon the latter is free to be projected by rotation of the handle in the manner previously indicated.

In order to prevent a coin deposited in the chute from rolling out of the open inner end thereof and thereby allowing the detent to return to locking position with respect to the plate 14 before the latter has been projected, an arm 28 is rotatably mounted on shaft 24 and at one end carries a pin 28' that is disposed normally across the inner end of the chute. The other end of this arm is formed into a cam member 29 so disposed as to be engaged by the plate 14 during forward or projectile movement of the same thereby to cause sufficient rotation of the arm to move the pin 28' upward and out of covering relation with the chute. Thus the coin is retained in the chute and by its weight holds the detent out of locking contact with the plate until the plate has been projected a predetermined distance, at least sufficient to prevent the detent from assuming a locking position with respect thereto, when the coin is released, which, as stated, occurs when the plate by its engagement with the cam 29 moves the arm 28 and pin 28' upward.

It is desirable that means be provided to effect a positive return impetus to the chute and detent to cause them to return quickly to normal positions following each projectile and subsequent retractile movement of the plate 14. This means constitutes a lug or projection 37 on the lower side of the chute and a spring pressed plunger 38 carried by the front upright 12 and engageable by the lug so as to be depressed thereby when increased rotation is imparted to the chute. Normally the lug and the plunger are slightly spaced relatively in order that the weight of the coin may be effective to rotate the detent sufficiently to disengage it from the plate 14, but immediately following this slight initial rotation the lug contacts with the plunger and upon increased rotation of

the detent and chute, such as is imparted by engagement of the plate 14 with the protuberance 31 on the arm 25, depresses the plunger against the action of the spring whereby the latter acts through said plunger and lug to impart a return momentum to the chute and detent when the plate 14 is retracted.

Means has been provided whereby the coin slot is closed when the articles A have been exhausted from the receptacle. This means consists essentially of a slide 39 that is longitudinally movable and that is effective to cover and uncover said slot, in combination with an upwardly spring pressed plunger 40 that is so disposed as to be depressed normally by the weight of the sheets contained in the receptacle, said plunger being so connected with the slide as by means of the bell crank arrangement 41 as to maintain the slide in uncovering relation with respect to the coin slot as long as the plunger is depressed. The weight of the last sheet A is insufficient to properly depress the plunger and therefore use is made of a weight bar 42 that is placed upon the superimposed sheets when the receptacle is filled. The weight of this bar holds the plunger depressed until the last sheet A has been projected, when it rises under the influence of its spring 43 through an opening 44 provided in the bar to permit such movement. This rise of the plunger acting through the bell crank arrangement 41 causes the slide to be moved to cover the slot in a manner that is apparent.

Below the chute is a lock controlled box 47 disposed to receive the coins as they fall from the chute.

From the foregoing description considered in connection with the accompanying drawings, it is believed that the construction, operation and advantages of our improved coin controlled device will be clearly understood and while we have herein shown and described one specific embodiment of our invention, we do not limit ourselves thereto, except for such limitations as may be defined in the appended claim.

We claim:

A coin control device for vending machines including, in combination, a receptacle for articles to be dispensed, a projectile and retractile plate movable to effect delivery of articles from said receptacle, a shaft below said plate, a coin chute pivotally mounted on said shaft, a member fixed with respect to said coin chute engaging said plate when the latter is retracted to prevent projection of the same, said coin chute being adapted to be tilted by the weight of a coin deposited therein to move said member out of engagement with said plate to permit the plate to be projected, a cam formation on said member engageable by the plate during

its projection to hold the coin chute in a tilted position, an arm intermediately pivoted on said shaft, and a pin on one end of said arm normally lying across the discharge end of said coin chute to retain a coin therein, the other end of said arm being disposed to be engaged by said plate following a predetermined amount of projectile movement

thereof to rotate said arm on said shaft and move said pin from across the delivery end 10 of the chute.

In testimony whereof we hereunto affix our signatures.

NICHOLAS CAMELO.
THOMAS DOMBROWSKI.
